CLAIM

The ornamental design for a rack for corkscrew, as shown and described.

DESCRIPTION

FIG. 1 is an elevational view of the front side of a rack for corkscrew, showing my new design, the rear surface thereof being flat and unornamented;

FIG. 2 is a left side view thereof;

FIG. 3 is a right side view thereof;

FIG. 4 is a bottom side view thereof; and

FIG. 5 is a top side view thereof.
